(57) **CLAIM**

We claim the ornamental design for a rotary impact wrench, as shown and described.

DESCRIPTION

FIG. 1 is a front perspective view of a rotary impact wrench embodying our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate portions of the rotary impact wrench that form no part of the claimed design.

1 Claim, 7 Drawing Sheets(56)
